MANUFACTURE OF ELEMENTS FOR SLIDE FASTENERS

Frederick Ulrich, New York, N. Y., assignor, by
mesne assignments, to Conmar Products Cor-
poration, New York, N. Y., a corporation of
New York

Application April 12, 1934, Serial No. 720,232

16 Claims. (Cl. 29—34)

This invention relates to slide fasteners, and more particularly to a method and apparatus for manufacturing the interlocking elements of such fasteners.

5 The primary and general object of my invention resides in the provision of an improved method and improved apparatus for forming the interlocking elements for slide fasteners, said elements being of the conventional type having interlocking means at one end and spaced jaws at the other end for clamping the element upon the beaded edge of a suitable tape. A more particular object of my invention is to minimize manufacturing cost by utilizing a simple slender strip or 10 conventional wire stock for raw material, said wire being uniform and regular in section. The elements are formed longitudinally of the wire, that is, in end to end relation, and the wire is preferably selected with a cross-section approximately equal to the transverse cross-sectional area of the fastener elements. A more particular object 15 is to make possible the use of ordinary round wire, that is, wire of standard circular cross-section, thereby reducing the cost of the raw material to a minimum and resulting in certain further advantages which will be brought out in the following specification.

Still another object of my invention is to greatly increase the convenience and ease of handling the embryo fastener elements during the various operations needed to form the same, and with this object in view I form the elements in pairs arranged head to head, thus providing twin units which are perfectly symmetrical and the jaw 20 portions of which are at the ends of the unit. This facilitates the operation of splitting the ends to form jaws, because the forces applied to the twin unit are opposed and in equilibrium. Likewise, the heads when treated as a pair form a symmetrical structure which is more readily swaged to shape, and the natural shape between the heads is such as to facilitate subsequent severance or separation of the elements making up the twin unit. Moreover, the twin unit, because 25 of its size and symmetry, is especially easy to control and move from station to station in the apparatus, in contrast with the difficulty of handling a single element.

Other objects of my invention reside in the provision of appropriate automatic apparatus for manufacturing the elements in accordance with the foregoing principles and which will include means for accommodating elongation of the bar or wire during the swaging operation and before 30 severing the units therefrom; which will positive-

ly hold and feed the units from station to station by means of an intermittently rotated or indexed dial cooperating with a stationary die table; as well as numerous additional objects which will be evident from the detailed description of the 5 apparatus.

To the accomplishment of the foregoing and such other objects as will hereinafter appear, my invention consists in the method and apparatus elements, as hereinafter are more particularly 10 described in the specification and sought to be defined in the claims. The specification is accompanied by drawings in which:

Fig. 1 is a section in elevation explanatory of 15 the swaging and severing of twin embryo units from round wire stock;

Fig. 2 is a plan view of the embryo twin unit;

Fig. 3 is an end view of the same;

Figs. 4 and 5 are, respectively, side and bottom views showing the splitting of the jaw portions 20 of the twin unit;

Figs. 6 and 7 are, respectively, side and bottom views showing the spreading of the jaw portions of the twin unit;

Figs. 8 and 9 are, respectively, side and bottom 25 views showing the shaving to final form of the jaw portions of the twin unit;

Fig. 10 is a side elevation showing the embossing of the interlocking portions of the twin unit to final form; 30

Fig. 11 is a side elevation illustrating the severing of the finished elements in the twin unit;

Fig. 12 is a section through a specially rolled wire or bar which may be used in my process;

Figs. 13 and 14 are, respectively, plan and ele- 35 vational view showing a preliminary indenting step which may desirably be used when dealing with flat or flattened bar stock;

Fig. 15 is a plan view of the die assembly of my apparatus; 40

Fig. 16 is a front elevation thereof;

Fig. 17 is a section taken in the plane of the line 17—17 of Fig. 15, and shows the mechanism for cutting the twin units from the wire;

Fig. 18 is a plan view of the dial plate forming 45 a part of the die assembly;

Fig. 19 is a section taken in the plane of the line 19—19 of Fig. 18, and shows the splitting punch;

Fig. 20 is a section taken in the plane of the 50 line 20—20 of Fig. 18, and shows the jaw spreading mechanism;

Fig. 21 is a section taken in the plane of the line 21—21 of Fig. 18, and shows the jaw shav- 55 ing punch;

- Fig. 22 is a section taken in the plane of the line 22—22 of Fig. 18, and shows the mechanism for separating the finished elements of the twin unit;
- 5 Fig. 23 is a side elevation of a press suitable for my purposes;
- Fig. 24 is a sectional elevation showing a two-stage swaging operation having certain advantages;
- 10 Fig. 25 is a plan view of round wire stock subjected to two swaging operations; and
- Figs. 26 and 27 are vertical and horizontal sections showing modified punch mechanism for separating the finished elements of a twin unit
- 15 swaged as illustrated in Figs. 24 and 25.
- Referring to the drawings and more particularly to Figs. 1 through 11, the method of my invention may be outlined as follows. A continuous round wire of suitable material 12 is
- 20 fed through a swaging die including a stationary die 14 and a vertically reciprocable swaging punch 16. The wire is generally flattened at the top and bottom during this swaging operation, and is additionally provided with heads 18 and
- 25 20 and opposed recesses 22 and 24. The wire is also longitudinally incised at the top and bottom, as is indicated at 26 and 28. The wire is supported at opposite sides of the swaging die by lifting pads 30 and 32. These lifting pads are
- 30 preferably closed above the wire, as is indicated at 34 and 36, in order to limit permissible upward movement of the wire. The lifting pads 30 and 32 are resiliently urged upwardly to the position shown in Fig. 1, thus lifting the swaged wire
- 35 clear of the die 14 after the swaging operation. The enclosure of the wire at 34 and 36 prevents upward movement of the wire with the swaging punch 16 at the end of the swaging operation, and insures stripping of the wire from the swaging punch. Downward movement of the swaging punch 16 is preferably accompanied by downward movement of yieldable fingers 38 and 40 which press the pads 30 and 32 downwardly and insure seating of the wire on the stationary
- 40 45 swaging die 14. The pad 32 is preferably cut away, as indicated at 42, so as not to obstruct movement of the head 20 through the pad.
- At the end of each swaging operation, the wire 12 is moved ahead a distance approximately equal
- 50 to the length of two fastener elements, thus bringing a fresh section of wire into the swaging die and moving the previously swaged sections toward a cutting-off punch 44. A spring pad 46 is located beneath the cutting-off punch 44, and a
- 55 stationary cutting blade 48 is inserted in and forms a part of the stationary member 50. It will be understood that downward movement of punch 44 shears the section or twin unit T from the continuous wire. In passing, it may be mentioned that the cutting-off punch 44 is preferably arranged to sever the unit T somewhat later than the swaging operation in the die 14, 16, in order to accommodate stretch or elongation of the material which takes place during the swaging operation.
- The resulting section or twin unit T is shown
- 60 in Figs. 2 and 3 which clearly illustrate the formation of the heads 18 and 20, the recesses 22 and 24, and the longitudinal incisions 26 and 28.
- 65 70 75 The side indentations 52 should also be noted because these partially define the heads of the embryo interlocking elements and are obtained without a special indenting operation by merely restraining the material to approximately the initial diameter of the wire.

The ends of the twin unit are next split, and this operation is shown in Figs. 4 and 5 in which it will be seen that the splitting punches 54 are forced downwardly through the incisions 26 and 28. The punches 54 are preferably acutely triangular in cross-section and beveled to a knife edge at the bottom ends, as is clearly shown in Fig. 5. A spring pad 56 is preferably arranged to descend with the splitting punches 54 in order to enter the recesses and to accurately locate and firmly hold the twin unit during the splitting operation.

The twin unit is next subjected to a spreading operation in order to spread apart the jaws of the embryo elements, and this spreading operation is shown in Figs. 6 and 7. The twin unit is supported between a spring pad 58 and a stationary table 60, while wedges 62 and 64 are moved in opposite directions into the split ends of the unit, thus bringing the jaws into desired divergent relation.

The inner walls of the jaws are then brought to a desired undercut shape by a shaving or trimming operation which is illustrated in Figs. 8 and 9. The twin unit is held between stationary die 66 and a spring pad and stripper 68, while shaving punches 70 are forced downwardly between the jaws. The shaving punches trim a small amount of metal from between the jaws, and leave the unit with the outline shown in Fig. 9. This outline is ideal for easy application to and secure mounting upon the conventional beaded tape.

The heads of the embryo elements may, if desired, be embossed to final accurate shape and dimension, and this operation is shown in Fig. 10 in which the twin unit is compressed between an embossing punch 72 and a stationary die 74. The punch 72 is accompanied and preceded by spring pins 76 which operate to support and steady the unit during the embossing operation and to strip the unit from the embossing punch when the punch is elevated. It will be noted that the embossing punch 72 helps shape the lips 78 of the elements and reduces to a minimum the metal connecting the heads of the elements.

The elements being otherwise completed, it is next necessary merely to separate the same, and this is done by an appropriate separating punch illustrated in Fig. 11. One of the elements is supported between a stationary die 80 and a spring pad 82, while the other element is forced downwardly by a separating punch 84 cooperating with a spring pad 86. The spring pad 82 is, of course, preferably reciprocable with and arranged to precede the separating punch 84 during its downward stroke.

With this preliminary explanation of my invention, attention may next be turned to apparatus for automatically performing the above operations. It will already be apparent, however, that my method of forming the elements from a continuous wire having a cross-sectional area approximately equal to the cross-sectional area of the element is characterized by numerous advantages, in that the raw material is in a conventional and economical form and is utilized without much waste. It will also be evident that manufacture of the elements in pairs arranged head to head, is advantageous because it is easier to handle the twin unit by reason of its size and symmetry; because the forces to which the unit is subjected are at all times inherently balanced, as during the swaging, splitting, and spreading operations; and because the shaping of the adja-

cent heads best utilizes the available metal and largely severs the elements.

Referring now to Fig. 23, I show a press **P** suitable for practicing my invention. This press is provided with a bed **90** and a vertically reciprocable head **92** which is reciprocated by an appropriate eccentric mounted on drive shaft **94**. Between the bed **90** and head **92** there is placed a die assembly **D**. This die assembly includes an auxiliary shaft **96** geared in any desired manner, as through helical gears **98**, intermediate shaft **100** and helical gears **102**, to the main drive shaft **94**. The die assembly **D** includes a punch plate **104** locked in reciprocable head **92** by an appropriate lock screw **106**.

In Figs. 15 and 16 I show the die assembly **D** in greater detail. The auxiliary shaft **96** and helical drive gear **102** therefor are clearly evident, as well as the vertically reciprocable punch plate **104** with its upstanding boss **105** adapted to be inserted in and locked to the press head **92** of Fig. 23. Punch plate **104** is guided by guide rods **108**. The die assembly includes wire straightening means **S**, wire feed means **F**, and a nest of dies or punches for the various operations heretofore mentioned, said punches being located beneath the punch plate **104** and being for the most part, though not entirely, actuated directly thereby. The operations up to severing the twin unit from the wire are performed in alignment with the wire **12**, while all succeeding operations upon the severed twin unit are performed about the periphery of a circle, the units being intermittently moved by a circular dial plate **110**, this dial plate being shown in greater detail in Fig. 18.

The wire straightening means **S** may be of any desired type, and in the present case comprises simply a series of suitably spaced rollers **112** mounted on vertical bearings, and a similar group of rollers **114** mounted on horizontal bearings. The wire **12** is drawn through the straightener and intermittently fed in measured increments by the feed means **F**. This feed means may be of conventional type and probably needs no further description than to say that the feed member **116** is reciprocated by a crank **118** through a connecting rod **120**, the crank **118** being mounted at the forward end of a shaft **122** geared to auxiliary shaft **96** by helical gearing **124**. The gripping or opening and closing of the feed element **116** is controlled by a cam **126** mounted on shaft **96** and cooperating with a cam follower **128** mounted at the end of a lever **130**, pivoted at **129**, and bearing against the clamp mechanism of feed member **116** through an anti-friction roller **131**, to permit reciprocation of the feed member. The feed of wire **12** may be controlled for accurate amount and timing.

The wire **12** then passes through a swaging die generally indicated at **132**. This swaging die corresponds to the die **14, 16** shown in Fig. 1, and is similarly accompanied by lifting and stripper pads, etc. The swaging punch **16** is mounted directly on punch plate **104** and is reciprocated thereby.

The cutting-off punch assembly is generally indicated at **134**. It was already mentioned, in connection with Fig. 1, that the cutting-off punch is preferably operated later than the swaging punch in order to accommodate elongation of the metal during swaging, and for this reason the cutting-off punch assembly **134** is preferably operated independently from shaft **96**, rather than from the main punch plate **104**. To this end, shaft **96** is provided with an appropriate

cam **136** cooperating with a cam follower **138** secured at one end of operating lever **140**, the opposite end of which is connected to the cutting-off punch **44**. This mechanism is better shown in Fig. 17 which further brings out special detent mechanism on the spring pad **46** for better cooperation with the rotatable dial **110**. Pad **46** is normally elevated by spring **142**. After cutting a twin unit from the wire, it is desirable to prevent elevation of spring pad **46** above the stationary table **144** in order not to interfere with the desired movement or indexing of the dial to the next station. For this purpose a reciprocable detent **146** is provided, this being operated through bell crank lever **148** by a cam **150** mounted on shaft **96**. The cams **136** and **150** are so relatively timed that detent **146** is moved into holding engagement with pad **46** shortly after downward movement of cutting-off punch **44**. The detent **146** limits the upward movement of pad **46** to bring the unit **T** level with table **144**, thus permitting sliding of the unit on table **144** by dial **110**. When the table has been moved to its next position, the pad **46** is, of course, released and elevated for cooperation with cutting-off punch **44** during the next shearing operation.

The dial **110** is provided with a ratchet wheel **152** and is moved by a pawl **154** (Fig. 15) mounted on a pawl plate **156** pivoted at **158** and carrying a cam follower **160** cooperating with a cam **162** mounted on shaft **96**. Return movement is prevented by suitable holding pawl **164**. It will be manifest that for each revolution of shaft **96**, the dial plate is advanced or indexed to the next station. The punch plate **104** is preferably provided with a special locating or indexing punch **166** the sole function of which is to lock the dial plate in exact position during the punching operations.

Referring to Figs. 15 and 18, the splitting operation is performed at the station **170**, the spreading operation at station **172**, the shaving operation at station **174**, the embossing operation at station **176**, while the elements are separated at station **178** and discharged from the dial plate at station **180**.

The mechanism at station **170** is shown in Fig. 19 in which it will be seen that the splitting punches **54** are fixedly mounted on punch plate **194** which further carries the spring pad **56** yieldable against compression spring **182**. The unit **T** rests upon the die table **144** and within one of the slots or compartments **184** (Fig. 18) of dial plate **110**. The table **144** is preferably provided with a circular groove **186** for receiving the heads of the unit **T** as the unit rests upon or is moved around the table.

The spreading mechanism of station **172** is shown in greater detail in Figs. 18 and 20. The wedge **62** is formed at one end of a plate **190** having a biased camming slot therein which cooperates with a sloping actuator or reciprocable cam **192**, said cam being fixedly mounted on the punch plate **104**. The opposite wedge **64** is mounted at one end of a reciprocable bar **196** provided with an oppositely sloped cam slot cooperating with an oppositely sloping portion **198** of the actuator or cam bar. It will be evident that upon downward reciprocation of punch plate **104**, the wedge **62** is moved to the right into one end of the unit **T**, while the wedge **64** is moved to the left into the opposite end of unit **T**. These forces counterbalance, and it is merely necessary to hold the unit against upward movement. This is readily

accomplished by the spring pad 58 yieldably mounted in punch plate 104.

The shaving or trimming mechanism at station 174 is shown in greater detail in Fig. 21. 5 Punch plate 104 carries a pair of shaving punches 10 rigidly mounted thereon, and further carries the spring pad and stripper 68. The table 144 preferably has inserted therein the female die member 200 cooperating accurately with the 10 shaving punches 10. The waste amount of material removed from the unit T is forced downwardly through the opening 202 in table 144.

The embossing mechanism at station 176 is not shown in detail, first, because the use of this 15 mechanism is optional and may, if desired, be dispensed with; secondly, because the mechanism is anyway shown in Fig. 10; and, thirdly, because it will be apparent that it is merely necessary to rigidly mount the embossing punch 72 20 and to yieldably mount the stripper pins 76 (see Fig. 10) on the punch plate 104.

The separating mechanism at station 178 is shown in Fig. 22 in which it will be seen that the 25 separating punch 84 is rigidly mounted on punch plate 104 and cooperates with spring pad 86 yieldably mounted in table 144. The downward movement of punch 84 is accompanied by spring pad 82 yieldably mounted in punch plate 104.

The discharge station 180 needs no detailed 30 description, it including simply a trap or opening through table 144 and a mating pusher or finger on punch plate 104 to insure that the elements will fall through the opening into an appropriate receptacle placed therebeneath.

35 In Figs. 12, 13, and 14 I illustrate a modification of my invention in which the raw material used, instead of being a simple wire of circular cross-section, is a wire or slender rod drawn to a special section corresponding to that desired for 40 the fastener elements. Fig. 12 shows a suitable wire having flattened sides 210 and preferably rounded edges 212. The material is fed through a swaging die in which twin units are formed, much as heretofore described, the die including a 45 vertically reciprocable swaging punch 216 cooperating with a stationary swaging die 214. When dealing with this material, however, it is desirable to precede the swaging operation with an indenting operation in which indentations 218 50 between the heads of the elements are formed by a pair of oppositely horizontally movable punches 220. The use of specially drawn material reduces the amount of deformation or swaging needed to form the elements, but increases the 55 cost of manufacture because the simple round wire stock is a standardized product purchasable at minimum cost.

The processes heretofore described may, if desired, be modified in several particulars. These 60 modifications are illustrated in connection with Figs. 24 through 27 of the drawings. The most important change shown in these figures is the formation of a broad substantial recess 230 between the heads of the elements, and the formation of the heads of the elements on top 65 instead of on bottom. This procedure necessitates cutting away a small section of metal between the heads when finally separating the elements of the twin unit, which results in a slight 70 additional waste of metal. However, the use of a sharp edge on the swaging die is avoided, and consequently the die is strengthened and its useful life greatly prolonged. Another advantage is the ability to accurately shape the outer edge 75 of the head. The intermediate operations, in-

cluding the splitting, spreading, and shaving operations, are similar to those heretofore described except that in each case the twin unit is preferably carried around the table by the dial plate with the heads uppermost instead of lowermost. 5 The embossing operation may be omitted. The separating mechanism differs from that heretofore described and will be described with reference to Figs. 26 and 27. The table 144 is provided with a female die 240. The material between the heads is cut away by a separating punch 242 which is strengthened at its edges by heels 244. The heels lie outside the elements, as shown in Fig. 27, but the punch may be curved so as to produce a rounded outline 248 at the 15 head of the element. This removal of material makes it possible to thin the outer edge or lip of the recess, and it is for this reason that the embossing operation is entirely unnecessary.

The table 144 is provided with spring pads 246 20 which rest beneath the jaw portions of the unit T. When punch 242 descends, the unit T is first forced downwardly with pads 246 and seated accurately on die 240. Continued movement of the punch cleanly cuts away the material between 25 the heads and separates the fastener elements. Upon upward movement of the punch the elements are raised by spring pads 246 to the level of table 144 and free of die 240. The next indexing movement of the dial readily shifts the now 30 separated elements along the table to the discharge station.

Reverting now to Figs. 24 and 25, the main swaging operation in the die 14, 16 may be preceded by a preliminary swaging operation in a 35 die 224, 226. The stationary dies 14 and 224 may be locked together as a single element, and the same applies to the movable swaging punches 16 and 226. Spring pads 30 and 32 are provided, as before. The object of the first swaging operation is to partially flatten the round wire stock, 40 as shown at 231, and to form the partial indentation 232 between the elements. This preliminary swaging operation lessens the necessary flow of metal in the next swaging operation and 45 avoids extreme distortion leading to bending of the wire. It obviously reduces the load on and consequently lengthens the life of the swaging dies. The changing form of the wire during the successive swaging operations is clearly evident 50 from Fig. 25.

It is believed that the method of my invention as well as the construction and operation of suitable apparatus for practicing the same, and the 55 many advantages thereof, will be apparent from the foregoing detailed description. The fastener elements are manufactured rapidly to accurate dimension at minimum cost, and are strengthened by the compression or swaging of the material. The elements are made with some but not 60 excessive waste of material, and from simple slender rod stock of uniform section which may desirably be circular, in which case the cost of the raw material is reduced to a minimum. Even with flattened material the section is simple and 65 such wire is more readily available and less costly than if given a complex irregular cross-section. The elements may be formed successively on the wire with the heads pointed all in one direction, but I obtain important additional advantages by 70 forming the elements in pairs, for the resulting twin units are large, symmetrical, and easy to handle; all of the forces applied to the units are inherently balanced; and the sloping surfaces 75 of the heads facilitate rather than complicate 75

subsequent separation of the elements. When using round stock instead of specially drawn flat stock, I obtain, in addition to the advantage of economy, a further advantage of some preliminary sideward indentation between the heads and the advantage of reducing the necessary extrusion of metal upwardly to form the head, for to some extent the head is formed by swaging metal downwardly around the head from an initial vertical dimension much greater than the thickness of flattened stock.

In the preferred form of apparatus in which a section of material is cut away between the heads (Figs. 24-27), I find that the swaging tools are strengthened and made capable of indefinite wear, while the head may be given a rounded outline and a thin lip without requiring particular refinement in the swaging operation. This cutting away of waste material between the heads may be applied to the flattened stock of Figs. 12-14, in which case the preliminary sideward indenting operation may be eliminated.

The apparatus is compact and relatively simple because a standard press may be employed and 25 the die assembly inserted in the press as a unit.

It will be apparent that while I have shown and described my invention in preferred forms, many changes and modifications may be made without departing from the spirit of the invention, defined in the following claims.

I claim:

1. An apparatus for manufacturing interlocking elements for slide fasteners, said apparatus including means to longitudinally feed a strip of material no wider than the transverse width of the elements, means to sever embryo elements in end to end relation from said strip, and means to split the ends of the elements to form divergent jaws.

40 2. An apparatus for manufacturing interlocking elements for slide fasteners, said apparatus including means to longitudinally feed a wire, a swaging die for preliminarily shaping the wire in the form of successive embryo elements, means to sever embryo elements from the wire, means to split the ends of the elements to form divergent jaws, and means to finish shaping the elements.

3. An apparatus for manufacturing interlocking elements for slide fasteners, said apparatus including means to longitudinally feed a wire having a cross-sectional area approximately equal to that of the elements, a swaging die for preliminarily shaping the wire in the form of successive elements, means to sever embryo elements from the wire, means to split the ends of the elements to form divergent jaws, and a shaving punch for removing a small amount of material from between the jaws and for shaping the same.

4. An apparatus for the manufacture of interlocking elements for slide fasteners including means to intermittently feed a wire, a swaging die for forming embryo elements, a cutting-off punch for severing embryo elements from the wire, and means for operating the swaging die and for operating the cutting-off punch later than the swaging die in order to accommodate elongation of the material during swaging.

5. An apparatus for the manufacture of interlocking elements for slide fasteners including means to intermittently feed a wire having a cross-sectional area approximately equal to the transverse cross-sectional area of the elements, a swaging die for forming opposed heads and recesses on said wire and for longitudinally incising jaw portions therebetween, a cutting-off punch

for severing embryo elements from the wire, and means for operating the swaging die and for operating the cutting-off punch later than the swaging die in order to accommodate elongation of the material during swaging.

6. An apparatus for the manufacture of interlocking elements for slide fasteners, each of said elements having a head at one end and jaws at the opposite end, said apparatus including means to feed a wire, a swaging die for forming pairs of opposed embryo elements arranged head to head, a cutting-off punch for severing said twin units from the wire, means to split the ends of the units to form jaws at the ends of the units, and means for separating the elements of each unit.

7. An apparatus for the manufacture of interlocking elements for slide fasteners, each of said elements having a head at one end and jaws at the opposite end, said apparatus including means to intermittently feed a continuous wire of cross-sectional area substantially equal to the transverse cross-sectional area of the elements, a swaging die for forming symmetrical sections approximately equal to the length of two elements with heads at the center portion of said sections, a cutting-off punch for severing the said sections from the wire, means for oppositely splitting the ends of the section to form divergent jaws, means for shaving said jaws, and means for separating the elements of each section.

8. Apparatus for the manufacture of interlocking elements for slide fasteners, each of said elements having a head and recess at one end and jaws at the opposite end, said apparatus including means to intermittently feed a continuous wire of round cross-sectional area substantially equal to the transverse cross-sectional area of the elements, a first swaging die for generally flattening the round wire in sections approximately equal to the length of two elements, a second swaging die for forming adjacent heads and recesses at the center portion of said sections, a cutting-off punch for severing the said sections from the wire, means for receiving and moving said sections past successive stations for oppositely splitting the ends of the section to form divergent jaws; for shaping said jaws; and for separating the elements of each section.

9. Apparatus for the manufacture of interlocking elements for slide fasteners, each of said elements having a head at one end and jaws at the opposite end, said apparatus including means to intermittently feed a wire, a swaging die for forming embryo elements in the wire, a cutting-off punch for severing elements from the wire in end to end relation, a stationary table surmounted by an intermittently rotatable dial plate, and means on said dial plate for receiving and moving the elements around the table through a series of stations for performing various finishing operations on the elements.

10. Apparatus for the manufacture of interlocking elements for slide fasteners, each of said elements having a head at one end and jaws at the other, said apparatus including means to intermittently feed a wire of cross-sectional area substantially equal to the transverse cross-sectional area of the elements, one or more swaging dies for forming units approximately equal to the length of two elements with adjacent heads at the center portion of said units, a cutting-off punch for severing the said twin units from the wire, intermittently rotatable means for receiving said units and for moving the same through a series of stations for performing various finish-

ing operations on the elements, the last of said stations including means for separating the elements of each unit.

11. Apparatus for the manufacture of interlocking elements for slide fasteners, each of said elements having a head and recess at one end and jaws at the opposite end, said apparatus including means to intermittently feed a continuous wire of round cross-sectional area substantially equal to the transverse cross-sectional area of the elements, a first swaging die for generally flattening the round wire in sections approximately equal to the length of two elements, a second swaging die for forming adjacent heads and re-15 ceases at the center portion of said sections, a cutting-off punch for severing the said sections from the wire, intermittently rotatable means for receiving said units or sections and for moving the same through a series of stations for per-20 forming various finishing operations on the elements, the last of said stations including means for separating the otherwise finished elements of each unit.

12. Apparatus for manufacturing interlocking elements for slide fasteners, said apparatus including a press having a stationary bed and a movable head, a die assembly mounted on said bed and including a punch plate secured to the head, feeding means for intermittently feeding a wire through the die assembly, one or more punches on said punch plate for preliminarily swaging the wire to form units each consisting of two embryo elements arranged head to head, a cutting-off punch for severing the twin units from the wire, intermittently rotatable means in said die assembly for receiving the units, and a series of finishing punches operated by the punch plate for finishing the formation and final separation of the elements between movements of the rotatable means.

13. Apparatus for manufacturing interlocking elements for slide fasteners, said apparatus including a press having a stationary bed, a movable head and a top shaft for reciprocating the same, a die assembly mounted on said bed and including a punch plate secured to the head, an auxiliary shaft geared to the top shaft for simultaneous rotation, feeding means operated by said auxiliary shaft for intermittently feeding a wire through the die assembly, one or more punches on said punch plate for preliminarily swaging the wire to form embryo elements, a cutting-off punch for severing elements from the wire, means on said auxiliary shaft for operating said cutting-off punch later than the swaging punches, intermittently rotatable means in said die assembly for receiving the elements, and a series of finishing punches operated by the punch plate for finishing the formation of the elements.

60 14. Apparatus for manufacturing interlocking

elements for slide fasteners, said apparatus including a press having a stationary bed, a movable head and a top shaft for reciprocating said head, a die assembly mounted on said bed and including a punch plate secured to the head, an auxiliary shaft forming a part of said die assembly and geared to the top shaft for simultaneous rotation, feeding means operated by said auxiliary shaft for intermittently feeding a wire through the die assembly, one or more punches on said punch plate for preliminarily swaging the wire to form units each consisting of two embryo elements arranged head to head, a cutting-off punch for severing the twin units from the wire, means on said auxiliary shaft for operating said cutting-off punch later than the swaging punches, a dial plate in said die assembly for receiving the units, pawl and ratchet means driven by said auxiliary shaft for intermittently rotating and indexing the dial plate, and a series of finishing punches operated by the punch plate for finishing the formation and final separation of the elements.

15. Apparatus for the manufacture of interlocking elements for slide fasteners, each of said elements having a head at one end and jaws at the other, said apparatus including means to intermittently feed a wire, one or more swaging dies for forming units approximately equal to the length of two elements with adjacent heads at the center portion of said units, a cutting-off punch for severing the said twin units from the wire, intermittently rotatable means for receiving said units and for moving the same through a series of stations for performing various finishing operations on the elements, one of said stations including means for separating the elements of each unit.

16. Apparatus for manufacturing interlocking elements for slide fasteners, said apparatus including a press having a stationary bed, a movable head, and a top shaft for reciprocating said head, a die assembly mounted on said bed and including a punch plate secured to the head, an auxiliary shaft geared to the top shaft for simultaneous rotation, feeding means operated by said auxiliary shaft for intermittently feeding a wire through the die assembly, one or more punches on said punch plate for preliminarily swaging the wire to form units each consisting of two embryo elements arranged head to head, a cutting-off punch for severing the twin units from the wire, means on said auxiliary shaft for operating said cutting-off punch later than the swaging punch, intermittently rotatable means in said die assembly for receiving the units, and a series of finishing punches operated by the punch plate for finishing the formation and final separation of the elements.

FREDERICK ULRICH.
